UNITED STATES PATENT OFFICE.

GOTTLIEB KUNDIG, OF NIEDERÖNZ, NEAR HERZÖGENBUCHSEE, SWITZERLAND

GRINDING-MACHINE.

1,032,686.

Specification of Letters Patent.

Patented July 16, 1912.

Application filed April 6, 1911. Serial No. 619,285.

To all whom it may concern:

Be it known that I, GOTTLIEB KÜNDIG, a citizen of the Swiss Confederation, and residing at Niederönz, near Herzogenbuchsee, Switzerland, have invented certain new and useful Improvements in Grinding-Machines, of which the following is a specification.

My invention relates to grinding machines, and a primary object is to provide an improved grinding machine comprising an automatic device which not only regulates the position of the grinding table or bench relatively to the grindstone, but enables the distance between the table or bench and the axis of the grindstone to be diminished exactly proportional to the wear of the grindstone.

I attain these ends by feeding the device more or less rapidly corresponding to the hardness of the grindstone, for which purpose the grindstone is contacted by at least one feeler which is connected in such manner with the aforesaid device that it is automatically held always at the same height as the edge of the grindstone.

One illustrative embodiment of my invention adapted for grinding files is represented by way of example in the accompanying drawings, wherein:

30. Figure 1 is a side elevation, partly in section, and Fig. 2 is a plan view.

Referring to the drawing, I provide on the main shaft 1 mounted rotatably in the support A of the file-grinding machine and carrying the grindstone 9, a worm 2 engaging a worm wheel 3 fast on the vertical shaft 4. Fast on the bottom end of this shaft 4 is a disk 5 carrying a radially displaceable pin 41. This pin is connected by a link 7 with a forked lever 6 able to rock about a vertical shaft 19. In this manner I arrange that, when the shaft 4 rotates, the lever 6 is reciprocated owing to the crank-like movement of the pin 41. The bushing 8 carrying the grindstone 9, is non-revolubly, but axially displaceably connected by a key 42 with the main shaft 1. This bushing has an annular groove 10 in which the antifriction rollers 11, journaled on the lever 6, engage with a suitable amount of play. In this manner I provide that, when the lever 6 is reciprocated, the bushing 8 and with it the grindstone 9 are pushed axially to and fro and in this manner the entire periphery of

the grindstone 9 is uniformly used in well-known manner.

In order to provide that the grindstone shall always project a constant distance beyond the surface of the table or bench which is integral with the frame 45 the following arrangement is made. The feeler levers 12, two of which are shown in the illustrative embodiment, are connected together on the one hand by a muff 13 non-revolubly, but axially displaceably connected by a key and groove with the axle 14. These feeler levers 12 are located close to the flat sides of the grindstone 9. The muff 13 has an annular groove 15 in which a two-armed forked lever 16 engages. This lever 16 is connected with the reciprocating mechanism of the grindstone 9 by a connecting rod 17 connected, if desired by means of a universal joint, to a lever 18 fast on the shaft 19, so that the feelers 12 are axially displaced on the axle 14 in the same manner as the grindstone 9 on the shaft 1. One end of the axle 14 is reduced and screw-threaded and attached by means of a nut 20 in the eye of a lever 20 which is fast on a revoluble shaft 21. In the illustrative embodiment the other end of the shaft 21 carries a lever 23 carrying a click 22. This click engages in a ratchet wheel 25 which is loose on the shaft 21 and is integral with the bevel gear 24 meshing with a bevel gear 26 fast on a shaft 27. This shaft carries a hand wheel 28 outside the frame 45, and within the latter a worm 29 meshing with a worm gear 30 fast on the shaft 31. This shaft 31 carries, in addition, a spur gear 32 meshing with a toothed rack 33 attached to the support A of the machine. The lever 23 has an arm 34, to which is attached the one end of a rope 35 running over a pulley 36, a weight 37 being carried by the other end of the rope. In the middle portion of the lever 20 is a set-screw 38 which abuts against the projection 44 of the table 43. Above the feelers 12 is the pressure roller 40 for the work-piece depressed by a weight 39.

My improved machine operates as follows:—The work-piece, *e. g.* a file, is fed by a horizontally and vertically displaceable holder to the grindstone 9 in such manner that the central axis of the file can be adjusted in position relatively to the grindstone in dependence on the shape of the file.

Such a holder is well known to all skilled in this art, as is also its arrangement just referred to; therefore, it is deemed that illustration and further description are unnecessary.

When assembling the machine the feelers 12 are adjusted by the set-screw 38 with their upper faces at the same height as the crown of the grindstone 9, and the weight 10 37 tends to keep them always in such a position that the screw 38 contacts with the projection 44. As soon as the grindstone is worn somewhat the feelers 12 are lowered by the work-piece, the shaft 21 is simultaneously rotated an amount corresponding to the wear of the grindstone, and the table 43 and its projection 44 are simultaneously lowered a corresponding amount, so that after the termination of the feed motion the projection 44 and the screw 38 contact one another. The new work-piece which is introduced consequently finds the feelers 12 always at the height of the crown of the grindstone 9, because the table, on which the work-piece lies, together with feelers 12 is moved downward by the feed mechanism corresponding to the wear of the grindstone 9, as will now be described. Namely, when the grindstone is worn away even a very 30 small amount, the feelers 12, as stated, are moved downward under the influence of the work-piece. The small rotatory motion of the shaft 21 is imparted to the click 22 which rotates the ratchet wheel 25, the bevel gear 24 and the bevel gear 26. Consequently the spur gear 32 on the shaft 31 rolls, owing to the worm gearing 29, 30, on the rack 33 fastened on the support A and moves the table 43 downward. As the entire feed 40 mechanism is mounted on the frame 45 it will descend with the latter, so that the levers 12, 20 again arrive in their original horizontal position relatively to the face of the table, and the click 22 rocks back sliding 45 with its arm 23 over the ratchet wheel. This operation is repeated automatically until the grindstone has become unusable and must be exchanged. As the table descends exactly the amount of the wear of the grindstone, the feed motion is relatively rapid when the grindstone is soft, and relatively slow when the grindstone is hard. If only one feeler lever be employed, it will move in a groove provided in the vertical central 55 plane of the grindstone. Such a simple change from the embodiment illustrated is regarded as not involving invention therewith and as not requiring illustration or further description for it to be understood by all persons skilled in this art.

If work-pieces are ground which are narrower than the grindstone, the slide which shifts the work-piece may be turned at any desired angle relatively to the axis of the 60 grindstone. One consequence thereof will

be that the work-piece will always contact with the two feeler levers or with the one single feeler lever. Also, the feelers 12 are hereby prevented from flying upward when a piece has broken out of the grindstone, for 70 example.

Instead of the one ratchet wheel 25, two or more ratchet wheels may be arranged one beside another in known manner having their teeth oppositely directed. The idle 75 motion of the click 22 in the gaps between the teeth is then reduced, because it sometimes engages with one and sometimes with another wheel. Also, friction gear adapted to feed the table continuously may be employed. Feed mechanisms of the character just mentioned are old in the arts and are recognized as well-known mechanical equivalents for the feed mechanism herein illustrated and hereinbefore described; therefore, further description and illustration are believed to be unnecessary.

Instead of the table being lowered corresponding to the wear of the grindstone, the height of the axle of the grindstone not being varied, the arrangement may be such that the position of the table is not changed but the axle of the grindstone is moved toward the table corresponding to the wear of the grindstone, this being brought about 90 in similar manner by means of feelers. These feelers may be arranged to rock as in the illustrative embodiment, or they may be displaceable in guides parallel with them. Obviously, it is possible to grind other work-pieces, such as surface plates and the like, with the above described grinding machine.

I claim:

1. In a grinding machine, the combination with a support; a main shaft journaled therein; and a grindstone mounted fast on said main shaft; of a frame having a bench arranged in operative relation to the grindstone, said frame being movable with respect to said support and grindstone; feed mechanism mounted in the frame for moving the same relatively to said support and grindstone; and a feeler which is operatively connected with said feed mechanism and actuates the latter to lower said frame as the 105 grindstone wears away.

2. In a grinding machine, the combination with a support; a main shaft journaled therein; and a grindstone mounted fast on said shaft and movable lengthwise thereof; of a frame formed with a bench arranged in operative relation to said grindstone, said frame being movable with respect to said support and grindstone; reciprocating mechanism driven by said shaft for moving said 110 grindstone axially back and forth therealong; feed mechanism mounted in the frame for moving the same relatively to said support and grindstone; and a feeler which is operatively connected with said feed mecha- 115

nism and actuates the latter to lower said frame automatically as the grindstone wears away.

3. In a grinding machine, the combination with a support having a toothed member; a main shaft journaled in said support; and a grindstone mounted fast on said shaft and movable lengthwise thereof; of a frame formed with a bench arranged in operative relation to the grindstone; an axle journaled in said frame; a toothed wheel fast on said axle and in mesh with said toothed member; a secend shaft journaled in said frame and provided with a bevel gear and a worm; a worm wheel mounted on said axle and in mesh with said worm; a feed shaft journaled in said frame; a loaded lever fast on said feed shaft; a ratchet wheel loose on said feed shaft; a bevel gear mounted loose on the latter and connected with said ratchet wheel and in mesh with the first-named bevel gear; a click carried by said lever; a second lever fast on said feed shaft and provided with a stop adapted to contact with said bench in its normal position; and a

feeler which is operatively connected with the last-named lever and which actuates the same to lower said frame automatically as the grindstone wears away.

4. In a grinding machine, the combination with a support; a main shaft journaled therein; and a grindstone mounted fast on said main shaft; of a frame having a bench arranged in operative relation to the grindstone, said frame being movable with respect to said support and grindstone; feed mechanism mounted in the frame for moving the same relatively to said support and grindstone; a feeler which is operatively connected with said feed mechanism and actuates the latter to lower said frame as the grindstone wears away; and mechanism for moving said feeler back and forth across the grinding face of the grindstone.

In testimony whereof, I affix my signature in the presence of two witnesses.

GOTTLIEB KÜNDIG.
